UNITED STATES PATENT OFFICE.

GEORGE E. RANDLES, OF CLEVELAND, OHIO, ASSIGNOR TO THE FOOTE-BURT COMPANY, A CORPORATION OF OHIO.

CLOTHES WRINGER.

Application filed August 28, 1924. Serial No. 734,571.

To all whom it may concern:

Be it known that I, GEORGE E. RANDLES, a citizen of the United States, residing at Cleveland, in the county of Cuyahoga and 5 State of Ohio, have invented certain new and useful Improvements in Clothes Wringers, of which the following is a specification.

The present invention relates to reversible 10 clothes wringers such as are used in connection with power driven washing machines and especially to the drain boards of such wringers.

In the construction of reversible clothes 15 wringers a drain board is provided which projects to each side of the wringer and during operation this drain board performs two functions, that of a drain for directing the water squeezed out of the clothes and 20 that of a clothes chute. At any particular time, the board on the side from which the clothes are being fed into the rolls serves as a drain for the water while that on the other side serves as a chute for the clothes.

25 In a modern washing machine, such as those equipped with a swinging wringer, it is desirable, in order to make the machine convenient for use, that the drain board projects quite a distance to each side of the wringer so as to carry the water a distance sufficient to direct it back into the tub from 30 which the clothes are being wrung even though the tub is not close up to the washing machine and to accomplish this result 35 without making the drain board too long and having it project too far down the drain board must be made with a comparatively small amount of pitch. As a result while 40 the drain board functions properly as a drain for the water it does not function so well as a chute for the clothes because it does not have enough pitch to cause the clothes to slide down it.

The object of my invention is to provide 45 an improved drain board for clothes wringers wherein the pitch of the drain board is adjustable so that the side of the board which is serving as a drain has a small amount of pitch and serves to direct the 50 water the desired distance away from the wringer while that side which is serving as a chute for the clothes has considerable pitch so that the clothes will slide down it readily.

55 For a consideration of what I believe to be novel and my invention, attention is di-

rected to the accompanying description and the claims appended thereto.

In the drawing, Fig. 1 is a side elevation of a clothes wringer provided with a drain board structure embodying my invention; 60 Fig. 2 is a transverse sectional view of the structure taken on line 2—2, Fig. 1; Fig. 3 is a detail sectional view taken on line 3—3, Fig. 2; Fig. 4 is a perspective, partly broken away, of one end of the drain board structure, and Fig. 5 is a plan view of one end of the structure.

65 Referring to the drawing, 1 indicates the frame of a wringer, 2 the rolls and 3 the openings in the frame through which the clothes are fed to the rolls. Only that part of the wringer is shown in the drawing which is necessary for illustrating my invention. The wringer structure illustrated is to be taken as typical of any suitable wringer 70 of the reversing type. For example, it may be a clothes wringer such as that shown in my Patent No. 1,520,887, granted Dec. 30, 1924.

75 The portion of the wringer frame beneath the rolls comprises side walls 4, end walls 5 and a bottom wall 6 which walls define a chamber which extends along beneath the rolls to receive water squeezed from clothes passing through the rolls. In bottom wall 6 is a longitudinally-extending central slot 7 through which the water runs onto the drain board structure, suitable guide flanges 8 being provided beneath the slot. The end walls of the wringer frame project downwardly as is indicated at 9 and at the corners of their lower inner edges are provided with inwardly-projecting lugs 10 and 10^a having flat top surfaces. There are thus two spaced 80 inwardly-projecting lugs at each end of the 95 wringer frame.

90 Supported on lugs 10 and 10^a and adapted to slide thereon is a water deflector comprising two longitudinally-extending, oppositely sloping walls 11 and 12 provided at 100 their juncture with a longitudinally-extending rib 13, and connected at their ends to end flanges 14. End flanges 14 are preferably formed integral with walls 11 and 12 and are of sufficient depth to serve to prevent 105 water running off the ends of walls 11 and 12. Connected to end flanges 14 are supporting walls 15 which rest on lugs 10 and 10^a and are adapted to slide thereon. Flanges 14 and supporting walls 15 are joined to 110

gether at their upper edges as is indicated at 16 and are slightly spaced apart leaving downwardly-opening recesses 17 at each end of the water deflector. The lower edges of 5 supporting walls 15 are straight and at their central portions they are provided with depending projections 18 which lie between lugs 10 and 10^a and limit the possible sliding movement of the deflector. Movement 10 of the deflector from the position wherein projections 18 are adjacent to or in engagement with lugs 10 as shown in Fig. 2, to a position wherein they are adjacent to or in engagement with lugs 10^a serves to move 15 deflector wall 12 from under slot 7 and bring deflector wall 11 under such slot, the rib 13 moving from one side of slot 7 to the other side.

The deflector is moved by means of a 20 crank or eccentric rod 20 which is pivoted at its ends in the end wall extensions 9 of the wringer frame and passes through vertical slots 21 in supporting walls 15. The throw of crank 20 is such as to move projections 25 18 from one pair of lugs 10 or 10^a to the other and the crank itself functions along with the lugs for limiting the movement of the deflector. Movement of the deflector from one extreme position to the 30 other serves to bring either wall 11 or wall 12 under drain slot 7. On one end of crank 20 is an operating handle 22 which may with advantage be made in the shape of an arrow to indicate for which direction of 35 wringing the drain board is adjusted, the arrow pointing in the direction the clothes are to pass through the wringer. Preferably the arrangement is such that crank 20 and handle 22 turn through an angle a little greater than 180 degrees in moving the 40 deflector from one position to the other. By this arrangement the crank moves somewhat beyond dead center so that it serves to lock the deflector in its adjusted positions. Also 45 the weight of the crank and the handle assist in locking the deflector.

Pivottally mounted on the deflector are two drains or chutes 23 and 24, the drain or chute 23 being on one side of the deflector and the drain or chute 24 being on the other side. They are provided with tapered side flanges 25 which at their inner ends are located within recesses 17 and receive pivot pins 26 which serve to connect the drains or chutes to the deflector. The 50 pivotal movement of the drains or chutes is limited on the one hand by the upper end of the drain or chute striking the under surface of deflector wall 11 or 12 and on the other hand by the top surface of the drain or chute engaging the outer edge of deflector wall 11 or 12, such edges in the 55 present instance being turned downward to provide flanges as indicated at 27. Lugs 10 and 10^a project inward to positions

wherein they stand under the side edges of drains or chutes 23 and 24 as is clearly shown in Fig. 1 of the drawing.

In Fig. 2 of the drawing, the drain board is shown as being in the position for wringing clothes through the wringer from left to right, the deflector being in its right hand position so as to bring wall 12 under slot 7. Drain or chute 23 is in its lowered position to form a chute of substantial pitch 70 down which the clothes will readily slide and it is held in this position by the engagement of its upper edge with the under side of wall 11. Drain or chute 24 is in its raised position for directing water away 75 from the wringer rolls and it is maintained in this position by being held between lugs 10^a and the down turned flange 27 on the outer edge of wall 12. Now as clothes are fed through the wringer, the water squeezed out of them is directed by walls 4 through 80 slot 7 onto deflector wall 12 and runs down this wall onto drain 24 and thence back into the tub.

Since flanges 25 are located outside end flanges 14 and flange 27 is in engagement 85 with the surface of chute 24, the water is well confined and directed so there will be no leakage off the sides of the deflector wall or drain. The clothes as they pass 90 through the wringer drop down onto drain 23 and slide along it into some suitable receptacle, the drain 23 having ample pitch 95 for causing the clothes to slide off it.

When it is desired to wring in the opposite direction, that is, from right to left in Fig. 2, crank 20 is turned by means of handle 22 in an anti-clockwise direction through an arc of about 180° thereby moving the deflector toward the left from the position shown in Fig. 2 to a position wherein projections 18 are adjacent to or in engagement with lugs 10^a. As the deflector moves toward the left, the under side of drain or chute 23 comes into engagement with the inner ends of lugs 10, and as the movement continues, the chute slides on the lugs and is raised by them, finally coming to a position corresponding to that of drain 24 in Fig. 2 wherein it is held between lugs 10 and the flange 27 on deflector plate 11. At the same time, drain or chute 24 slides off lugs 10^a and drops down into a position corresponding to the 105 position of drain 23 in Fig. 2. The drain board is now in position for wringing clothes through the wringer from right to left, deflector plate 11 being positioned under slot 7, drain 23 being held in its upper 110 adjusted position, and drain 24 being lowered so that the clothes will slide off of it 115 readily. In this connection, it is pointed out that the construction is such that the drain or chute when in its lowered position, 120 has a pitch such that the clothes will slide 125

off it readily without assistance. By this arrangement, therefore, the operator does not have to bother pushing the clothes off the drain or chute and so all the attention 5 of the operator can be devoted to feeding the clothes to the wringer.

Since the adjustment of the drain or chute is automatic, it requires no special attention on the part of the operator, the operation 10 for having merely to shift the drain board in the usual manner.

While the device is automatic in operation it is at the same time simple in structure and capable of being manufactured at a low 15 cost.

In accordance with the provisions of the Patent Statutes, I have described the principle of operation of my invention, together with the apparatus which I now 20 consider to represent the best embodiment thereof, but I desire to have it understood that the apparatus shown is only illustrative and that the invention may be carried out by other means.

25 What I claim as new and desire to secure by Letters Patent of the United States, is:—

1. In a reversible clothes wringer, an adjustable drain board comprising a member on each side of the wringer which at one 30 time serves as a drain for water and at another time as a chute for the clothes, and means whereby when the drain board is adjusted the member which is to serve as a water drain is elevated and the member 35 which is to serve as a clothes chute is lowered.

2. In a reversible clothes wringer, a frame having an opening through which water squeezed from the clothes is discharged, a drain board having oppositely sloping members, said drain board being 40 movable to bring either member under the slot, and means whereby when the drain board is moved to bring one member under the slot the other member is automatically 45 lowered to form a chute for the clothes passing through the wringer.

3. In a reversible clothes wringer, a frame having an opening through which water 50 squeezed from the clothes is discharged, a deflector having oppositely sloping walls, said deflector being movable to bring either wall under said opening, a drain pivotally connected to each side of the deflector, said 55 drains being adapted to be raised and lowered in accordance with the positions of the deflector, and means on the frame with which the drains engage when the deflector is moved for effecting the raising of the 60 drains.

4. In a clothes wringer, a frame, rolls journaled therein, a sliding drain board structure comprising a pivoted drain, inwardly projecting lugs on the frame upon which the drain board structure slides, the 65 ends of said lugs lying under the edges of the drain and adapted to be engaged by it when the drain board structure is moved to effect a raising and lowering of the drain on its pivots. 70

5. In a clothes wringer, a frame, rolls journaled therein, a sliding drain board structure comprising two pivoted drains either of which may be moved to a position to receive water wrung from clothes 75 passing through the wringer, the other then serving as a chute for the clothes, and lugs on the wringer frame upon which the drain board structure slides, the ends of said lugs lying under the edges of the drains and 80 positioned to be engaged by the drains during sliding movements of the drain board structure to effect elevation of the drains.

6. In a clothes wringer, the combination 85 of a frame, rolls therein, a deflector which may be adjusted to direct water coming from the rolls in either direction, drains which receive the water from the deflector, and means whereby when the deflector is adjusted the drain which is to receive the 90 water is elevated, the other drain being lowered to serve as a chute for the clothes passing through the wringer.

7. In a clothes wringer, the combination 95 of a frame, rolls therein, a deflector which may be adjusted to direct water coming from the rolls to either side of the wringer, a pivoted drain on each side of the wringer either of which may receive water from the deflector, and means whereby when the deflector is adjusted the drain which is to receive water from it is automatically 100 elevated and the other lowered.

8. In a clothes wringer, the combination 1 of a frame, rolls therein, a deflector having oppositely-sloping walls, lugs on the frame upon which the deflector slides to bring either wall in position to receive water from the rolls, drains pivoted to said deflector with their upper ends lying beneath the deflector walls and adapted to engage such walls to limit their downward movement, their upward movement being limited by the ends of the deflector walls, and means whereby when the deflector is moved the drains are automatically adjusted.

In witness whereof, I have hereunto set my hand this 25th day of August, 1924.

GEORGE E. RANDLES.
